(57) **CLAIM**

The ornamental design for a magnetic resonance tomography apparatus, as shown and described.

DESCRIPTION

FIG. 1 is a front view of a magnetic resonance tomography apparatus showing my new design;
FIG. 2 is a back view of the magnetic resonance tomography apparatus shown in FIG. 1;
FIG. 3 is a top view of the magnetic resonance tomography apparatus shown in FIG. 1;
FIG. 4 is a bottom view of the magnetic resonance tomography apparatus shown in FIG. 1;
FIG. 5 is a right side view of the magnetic resonance tomography apparatus shown in FIG. 1;
FIG. 6 is a left side view of the magnetic resonance tomography apparatus shown in FIG. 1; and,
FIG. 7 is a perspective view of the magnetic resonance tomography apparatus shown in FIG. 1.
Portions of the magnetic resonance tomography apparatus shown in broken lines form no part of the claimed design.
